INVENTOR
Frederick W. Martin.

by *Edward A. Wright, Atty.*

UNITED STATES PATENT OFFICE.

FREDERICK W. MARTIN, OF NEW YORK, N. Y., ASSIGNOR TO FRANKLIN RAILWAY SUPPLY COMPANY, OF WILMINGTON, DELAWARE, A CORPORATION OF DELAWARE.

DRIVING-BOX WEDGE DEVICE.

1,268,747.

Specification of Letters Patent. Patented June 4, 1918.

Application filed September 1, 1917. Serial No. 189,295.

To all whom it may concern:

Be it known that I, FREDERICK W. MARTIN, of the borough of Queens, county of Queens, in the city and State of New York, have invented a certain new and useful Improvement in Driving-Box Wedge Devices, of which improvement the following is a specification.

This invention relates to means for taking up wear between the driving boxes and the pedestals of locomotives, and has for its object to provide an improved wedge device for this purpose which shall operate automatically to take up the wear and at the same time allow sufficient freedom of movement between the parts to prevent sticking and permit the usual movements of the driving box relative to the frame.

In the accompanying drawing, Figure 1 is a side elevation of a pedestal and portion of the frame, with the driving box and wedge device shown in vertical section; Fig. 2 a horizontal section taken on the line 2—2 of Fig. 1; and Fig. 3 a horizontal section 25 taken on the line 3—3 of Fig. 1.

According to the construction shown the driving box 6, having flanges 7 and 8, is mounted between the pedestal jaws 4 and 5. The face of the jaw 4 is inclined and operates with the face of the adjusting wedge 9, which is pressed upward by the action of the spring 12. The opposite face of wedge 9 is preferably vertical and engages one side of the floating plate 10, preferably having parallel vertical sides and located between the wedge 9 and the driving box 6.

The pedestal jaw 4 at the opposite side of the driving box, is provided with a straight vertical face and between this jaw and the driving box are located the shoe 15, tapering slightly in the same direction as the wedge 9, and the floating wedge 14, one face being slightly inclined to correspond with the face of the shoe and the other straight face engaging the box. The length of the floating wedge 14, and of the floating plate 10 are such as to allow a slight clear-

ance between said parts and the frame 17 at the top and the binder 16 at the bottom. 50

The wedges may be guided by separate strips 11, bolted to the pedestal jaw, as shown in Fig. 2, or by integral flanges on the wedge, as indicated in Fig. 3.

The spring 12 acts to force the adjusting wedge 9 upward to automatically take up the wear of the parts and maintain a snug fit of the driving box in the pedestal, but at the same time there will be no tendency for the wedges to stick or interfere with the free vertical movement of the box relative to the frame under the action of the vehicle springs. When there is an upward movement of the driving box the wedge 14 moves with it and relieves any binding action at the inclined face of the shoe 15. When there is a downward movement of the box relative to the frame it will carry the floating plate 10 with it to the extent of the clearance between the lower end of the plate and the binder. This movement will also be transmitted to the wedge 9, tending to pull the same down slightly or sufficiently to relieve any binding action and prevent sticking.

Having now described my invention what 75 I claim as new and desire to secure by Letters Patent, is:

1. The combination with a pedestal jaw having an inclined face, and an adjusting wedge coöperating therewith, of a shoe engaging the pedestal jaw at the opposite side and having an inclined face toward the driving box. 80

2. The combination of an adjusting wedge tapered in one direction at one side of the 85 driving box, a floating wedge tapered in the opposite direction at the other side of the driving box, and a shoe having an inclined face engaging said floating wedge.

3. The combination with a pedestal jaw 90 having an inclined face, and an adjusting wedge coöperating therewith, of a shoe having an inclined face at the opposite side of the driving box, and a floating wedge between said shoe and the driving box. 95

4. The combination of an adjusting wedge

and a floating plate located between a pedestal jaw and the driving box at one side, and a shoe and a floating wedge located between the other pedestal jaw and the box at the other side.

5. The combination with a pedestal jaw having an inclined face and an upwardly tapered wedge and a floating plate between

said face and the driving box, of a shoe engaging the other pedestal and having an inclined face, and a downwardly tapered floating wedge between said shoe and the driving box. 10

In testimony whereof I have hereunto set my hand.

FREDERICK W. MARTIN.
